R. W. RHODES.
WOODWORKING TOOL.
FILED JUNE 28, 1922.

INVENTOR
Robert W. Rhodes,

Bynes, Stevens & Pardee,
his attoys.

UNITED STATES PATENT OFFICE.

ROBERT W. RHODES, OF GREENSBURG, PENNSYLVANIA.

WOODWORKING TOOL.

Application filed June 28, 1922. Serial No. 571,500.

To all whom it may concern:

Be it known that I, ROBERT W. RHODES, a citizen of the United States, residing at Greensburg, in the county of Westmoreland, 5 State of Pennsylvania, have invented a new and useful Improvement in Woodworking Tools, of which the following is a full, clear, and exact description.

The present invention relates broadly to 10 wood-working tools and more particularly to tools of the type ordinarily referred to as scrapers and adapted for use in finishing floors and other surfaces.

In my co-pending application, Serial No. 15 538,843, filed February 24, 1922, patented Nov. 7, 1922, No. 1,434,914, I have disclosed and claimed a scraper comprising a blade of wafer-like thickness adapted to be clamped in curved position between suitable 20 members and to be adjusted by relative movement between said members. I have found that such a construction has certain disadvantages in that each adjustment changes the relative positions of the operating parts. By the present invention this difficulty is entirely obviated by the provision of means for adjusting the position of the blade independently of the clamping and supporting members.

The present invention retains all of the advantages of the construction disclosed in my co-pending application in that it enables the use of a scraping blade of inexpensive construction which can be easily resharpened 35 and which presents an effective cutting edge at all times.

In the accompanying drawings there is shown for purposes of illustration only one embodiment of the present invention, it being understood that the drawings do not define the limits of my invention and that changes may be made in the construction and operation without departing from the spirit of the invention or scope of my 45 broader claims.

In the drawings, Figure 1 is a side elevation, partly in section, illustrating one embodiment of the present invention;

50 Figure 2 is a top plan view of the end portion of the scraper illustrated in Figure 1, one of the operating handles being removed therefrom;

55 Figure 3 is a detail sectional view on the line III-III of Figure 2, the handle being

shown in position and certain of the parts being illustrated in elevation;

Figure 4 is a detail sectional view on an enlarged scale on the line IV-IV of Figure 2, and

Figure 5 is a front elevation of the scraping blade.

In the illustrated embodiment of the invention there is provided clamping means for the scraping blade 2 comprising a supporting member 3 and a backing member 4. Both the supporting member and the backing member have their cooperating faces curved, one to present a concave surface and the other a convex surface, whereby the 70 clamping operation will be effective for curving the scraping blade.

The supporting member 3 may be carried by arms 5 projecting downwardly from enlarged bearing portions 6 having openings formed therein to receive a transversely extending pin 7. Extending rearwardly from the bearing portions 6 are arms 8 lying in parallel spaced relation, as clearly shown in Figure 2 and provided with enlarged bearing portions 9 at their outer ends.

The backing member 4 may be formed to comprise spaced parallelly extending side members 10 adapted to embrace the arms 8, the backing member itself extending transversely with respect to the side members as will be clearly apparent. The side members at their forward portions are provided with bearing openings adapted to extend in axial alignment with the openings formed in the bearing portions 6 and receive the ends of the pin 7. The side walls at their rear portions preferably have solid portions adapted to embrace the bearing portions 9 formed on the arms 8. By reason of this construction the side members are effective for maintaining in operative position a pin 11 extending through the bearing portions in the arms 8 and having its ends abutting against the inner surfaces of the walls 10.

For maintaining the clamping members in the desired position and permitting operation thereof, there may be provided a handle 12. This handle is preferably keyed to a handle bar 13 which extends longitudinally through a spacing sleeve 14 and engages a transversely extending threaded opening in the pin 7. The end of the sleeve 14 adjacent the clamping members may be provided with a curved clamping face 15 adapted to en-

gage the front bearing portions formed on the supporting and backing members. By reason of this construction, it will be apparent that upon rotation of the handle 12 5 in one direction the sleeve 14 will be moved to release the clamping members and permit angular adjustment thereof relatively to the handle bar, while movement of the handle in the opposite direction will be effective for 10 clamping the parts in their adjusted position.

For moving the supporting member 3 relatively to the backing member 4 to clamp the blade in position, there is provided a second 15 handle 16 operatively secured in any desired manner to the stem 17 which is provided with a threaded lower portion 18 adapted to engage an interiorly threaded transversely extending opening formed in the pin 11. 20 Loosely surrounding the stem 17 is a clamping plate 19 formed with a flat upper surface adapted to permit rotational engagement with the handle 16 and with a curved lower surface adapted to engage the 25 side walls 10. These side walls at their rear portions are preferably curved in such manner as to provide arcuate bearing surfaces whereby when the handle 16 is turned in one direction to release the clamping member 19 30 the handle may be swung bodily, together with the pin 11 to change the effective position of the handle with respect to the clamping members. In this manner the effective downward pressure which may be exerted 35 by the handle 16 may be easily varied.

In addition to providing an adjustable mounting for the handle 16, the threaded stem 17 is also effective for clamping or releasing the blade. It will be apparent that 40 during the clamping operation the stem 17 is threaded into the pin 11 and thereby swings the supporting member 3 about the pin 7 as an axis. When the blade is being released, the reverse operation occurs.

45 For adjusting the position of the blade with respect to the clamping members, I have provided adjusting bars 20 having hooked lower ends 21 adapted to extend through the openings 22 in the blade 2 and 50 with threaded upper ends 23. These bars are vertically adjustable in sockets 24 formed in the backing member 4 outside of the walls 10, and having enlarged interiorly threaded recesses 25 at their upper portions.

55 The supporting member 3 may be provided with slots 26 to cooperate with the lower hooked ends of the bars 20. Threaded upon the upper ends of the bars and also having a threaded engagement with the recesses 25 are nuts 27. These nuts preferably have threads of different characters cooperating respectively with the bars and with the recesses whereby the movement of the nuts will be effective for imparting an amplified movement to the blade. This may

be accomplished by providing a left-handed thread on the bars 23 and a right-handed thread in the recesses 25, or vice versa, as will be apparent.

The scraping operation may be facilitated 70 by providing a foot 28 having a stem 29 adjustably engaging the socket 30 which is slidably mounted on the sleeve 14 and which may be clamped in adjusted position thereon by the set screw 31. In some instances 75 it is desirable to move the foot 28 from the position shown in full lines in Figure 1 to the position illustrated in dotted lines therein for permitting the scraper to be operated in a manner similar to the operation of a 80 plane. It will be apparent that by adjusting the position of the foot, the width of the throat provided between the same and the cutting edge of the blade may be accurately regulated.

85 It has been found desirable to mount the stem 29 nearer one end of the foot 28 than the other, as this permits the foot to spring upwardly a slight amount at its relatively free end when sufficient pressure is applied 90 to the handle 16. This enables the operator to easily remove a greater amount of material in small local areas, as may be desired.

95 The locking member 4 is preferably so shaped as to provide a small portion 32, as clearly shown in Figure 4, extending at an angle or curved with respect to the lower portion of the back edge of the backing member. The scraper during operation may be easily rocked over a wide angle about this 100 portion, thereby providing another means for determining and regulating the depth of cut. This operation is independent of the provision of the foot 28.

105 With the present construction it will be obvious that the position of the scraping blade is adjustable relatively to both of the clamping members and independently of the position of the handle 12. This permits the blade to be advantageously adjusted while 110 maintaining the outer parts in the desired angular relationship.

115 Further advantages of the present invention arise from the provision of an angularly adjustable handle 16 permitting the effective leverage thereof with respect to the scraping blade to be varied as desired.

I claim:

1. In a scraper, a flexible blade, members for clamping and curving the blade, and means for adjusting the position of the cutting edge of the blade relatively to the clamping members, substantially as described.

120 2. In a scraper, a flexible scraping blade, members for clamping and curving the blade, and vertically adjustable means for varying the position of the cutting edge of the blade relatively to the clamping members, substantially as described.

3. In a scraper, a flexible blade, means for clamping and curving the blade, means for adjusting the position of the cutting edge of the blade, and means forming an adjustable throat through which the material removed by the blade may pass, substantially as described. 5
4. In a scraper, a flexible blade having an opening therein, means for clamping and curving the blade, an adjustable means carried by said clamping means and provided with a projection engaging the opening in said blade, and means for adjusting the position of said last named means to adjust the position of the blade, substantially as described. 10
5. In a scraper, a flexible blade having a plurality of openings therein, means for clamping and curving the blade in operative position, and a plurality of independently adjustable means engaging the openings in said blade for adjusting the position of the cutting edge thereof, substantially as described. 20
6. In a scraper, a supporting member, a backing member, a flexible blade, means for clamping said blade in position between said members, said clamping operation being operative to curve the blade, means for adjusting the position of the blade relatively to both of said members, and a handle for operating the scraper, substantially as described. 30
7. In a scraper, a supporting member, a backing member, a flexible blade, means for clamping said blade in position between said members, said clamping operation being operative to curve the blade, means for adjusting the position of the blade relatively to both of said members, a handle for operating the scraper, and an adjustable foot cooperating with said blade and adapted to form therewith an adjustable throat through which the material removed by said blade may pass, substantially as described. 40
8. In a scraper, a supporting member, a
- backing member, said members having curved cooperating faces adapted to curve a blade clamped therebetween, a scraping blade, means for clamping said blade between said members, and means for adjusting said blade relatively to said members to vary the amount of projection thereof, substantially as described. 50
9. In a wood-working tool, a flexible blade of wafer-like thickness, supporting members for curving said blade and means for effecting relative adjustment between said blade and said members to vary the amount of projection of said blade, substantially as described. 55
10. In a wood-working tool, a flexible blade of wafer-like thickness, supporting members for clamping said blade therebetween with a deflective stress, and means for adjusting the position of said blade relatively to both of said members, substantially as described. 65
11. In a scraper, a flexible blade, means for clamping said blade with a deflective stress, and adjusting means for said blade comprising a threaded blade engaging member and an oppositely threaded nut engaging said member for adjusting the position thereof, substantially as described. 70
12. In a scraper, a flexible blade, means for clamping the blade with a deflective stress, an operating handle for said scraper and a second handle adapted to be swung to different positions to vary the effect thereof on the scraping blade when the scraper is being operated, substantially as described. 75
13. In a scraper, a blade, means for clamping the blade in position, an operating handle, and a foot of resilient material adapted to flex and cooperating with said blade for regulating the depth of cut thereof, substantially as described. 85

In testimony whereof I have hereunto set my hand.

ROBERT W. RHODES.
